UNITED STATES PATENT OFFICE.

FREDERICK H. BEROLD, OF WYOMING, OHIO.

SHEET-DELIVERY MECHANISM.

1,234,121.

Specification of Letters Patent. Patented July 24, 1917.

Application filed November 28, 1913. Serial No. 803,562.

To all whom it may concern:

Be it known that I, FREDERICK H. BEROLD, a citizen of the United States, residing at Wyoming, in the county of Hamilton and 5 State of Ohio, have invented certain new and useful Improvements in Sheet-Delivery Mechanism, of which the following is a specification.

My invention relates to sheet delivery 10 mechanism applicable for employment in delivering sheets in printing machinery, ruling machinery, bronzing machinery, and the like. I have illustrated the same in connection with a printing machine, and I shall so describe the same.

The actuating means for the sheet-receiving device herein shown and described are also shown, described, and are claimed in a 20 companion application for patent on improvements in sheet delivery mechanism, executed by me of even date herewith, filed November 28, 1913, Serial No. 803,561, and are therefore herein not more particularly claimed, the parts and the relations of parts 25 which are however not shown and described in said companion application, being herein claimed.

It is the object of my invention to provide 30 novel means for removing the sheet from the sheet-receiving device; further to provide novel adjusting means for said removing means; further to provide novel means for timing the relations of operation between the sheet-receiving device and the sheet-receiving device, and the invention will be 35 readily understood from the following description and claims, and from the drawings, in which latter:

Figure 1 is a side elevation of my improved 40 device, shown in connection with so much of a printing machine as is necessary to illustrate my invention.

Fig. 2 is a central vertical longitudinal section of the same, taken on the line 2-2 of 45 Fig. 3.

Fig. 3 is a horizontal section of the same taken on a line corresponding to the line 3-3 of Fig. 2.

Fig. 4 is a vertical longitudinal section, 50 taken on the line 4-4 of Fig. 3, showing one of the sprocket-chains and its attendant mechanism.

Fig. 5 is a cross-section of the same taken on the line 5-5 of Fig. 4.

55 Fig. 6 is a cross-section of the same taken on the line 6-6 of Fig. 4.

Fig. 7 is a cross-section of the same, taken on the line 7-7 of Fig. 4.

Fig. 8 is a horizontal section of the same, taken on the line 8-8 of Fig. 7.

Fig. 9 is a cross-section showing the gripper mechanism of the transfer cylinder, on a line corresponding to the line 9-9 of Fig. 3.

Fig. 10 is a cross-section on the line 10-10 of Fig. 3, showing the stripper mechanism, 65 partly broken away.

Fig. 11 is a rear end elevation, partly broken away, of the adjusting means for the stripper mechanism.

Fig. 12 is an inside elevation of the adjusting and operating means of the stripper mechanism, partly in section on the line 12-12 of Fig. 3; and,

Fig. 13 is a longitudinal section of the buffer means, taken on the line 13-13 of 75 Fig. 3.

21 represents the main cylinder, shown as an impression cylinder, journaled in suitable bearings in the main frame 22 of the machine and coöperating with a suitable type or plate cylinder, hereinafter referred to as a plate cylinder 23. This plate cylinder is on a shaft 24 journaled in suitable bearings in the main frame. The sheet to be printed or otherwise operated upon is 85 fed from a suitable feed-board 25, and is acted on by suitable grippers 26 on the impression cylinder, operated in suitable manner for carrying the sheet about the impression cylinder and delivering it to a 90 transfeerer 27. This transfeerer comprises a shaft 30 journaled in bearings 31 in the main frame. It has a gear 32 thereon driven in suitable manner from a gear on the shaft 24.

A suitable number of sheet-supporting rolls 33 and draw-rolls 34 are mounted on the shaft 30 and are adjustably placed lengthwise of said shaft, as by means of set-screws 35. The supporting rolls have 100 serrated peripheries 36 for reducing contact thereof with the sheet to the minimum, and the draw-rolls have narrow peripheries 37 arranged to be placed at suitable points crosswise of the sheet. The rolls on the 105 shaft 30 are provided with grippers 38 which coact with gripper-faces 39 on said rolls, and are respectively secured to a gripper-shaft 40 journaled in bearings 41 in said rolls.

46, 47, are a pair of bearer-disks which coöperate with bearer-disks 48 on the

impression cylinder. The bearer-disk 46 forms a housing for mechanism for operating the gripper-shaft 40. The gripper-shaft 40 is journaled in a bearing 49 in the bearer-disk 46 and has a segment-gear 50 rigid thereon. An arm 51 is pivoted on a pin 52 secured in the bearer-disk 46 and has a segment-gear 53 thereon which meshes with the segment-gear 50. The gripper-shaft 40 has an arm 54 rigid thereon with which a rod 55 is articulated at 56. A spring 57 is coiled about said rod and is located between a shoulder 58 on said rod and a rocking bearing 59 on a pin 60 in the bearer-disk 46. The arm 54 is arranged to strike a stop 62 for limiting the sheet-contacting movement of the grippers 38 urged by the spring.

63 is a cam secured to the main frame about which a roller 64 on the arm 51 rotates for operating the grippers 38. The grippers 38 of the transferrer are arranged to grip the forward edge of the sheet as the same is released by the grippers on the impression cylinder, for transferring the sheet from the impression cylinder to the transferrer and delivering the same to the sheet-receiving device.

30 This delivery of the sheet to the sheet receiving device from the transferrer is accomplished by the draw-rolls 34 and coacting draw-rolls 68, the latter adjustably positioned lengthwise of a shaft 69 by set-screws 70. The shaft 69 is journaled in bearings 71 on levers 72 secured to a rock-shaft 73 journaled in bearings 74 in the main frame. A set-screw 75, received through each of the levers against a rigid part of the main frame, positions the coacting draw-rolls with relation to the draw-rolls on the shaft 30, the coacting draw-rolls in practice being spaced a distance from the draw-rolls just sufficient to make firm contact with the sheet on both sides thereof for directing the sheet 40 in a direction between said draw-rolls toward the sheet-receiving device, where it is delivered printed or wet side up. The shaft 69 has a gear 76 fast thereon which is meshed by the gear 32 fast on shaft 30 of the transferrer.

50 The sheet-receiving device is instanced as a reciprocating carriage 81 having sheet-supports thereon, shown as delivery-sticks 82 thereon. The carriage comprises side-frames 83 mounted on wheels 84 rotating on axles 85 secured in bearings 86 of the side-frames. The side-frames are connected by a cross-bar 87 rigid therewith. The cross-bar has saddles 88 adjustably secured thereto, the saddles having the delivery-sticks 82 secured thereto as by screws 89. The saddles are adjustable lengthwise of the cross-bar for positioning the delivery-sticks at suitable points crosswise of the machine.

65 The wheels 84 move lengthwise of the

machine between tracks 90, 91, for moving the carriage forward and back under the transferrer.

The carriage is reciprocated by means of flexible propelling means arranged in oppositely moving stretches received at their ends about rotating supports, and shown as sprocket-chains 96 which pass about sprocket-wheels 97, 98, for forming stretches 99, 100, supported on guides 101, 102. Each of the 75 sprocket-wheels 97 is fast on a stud-shaft 103, journaled in a bearing 104 in the frame. Each of the stud-shafts has a gear 105 thereon which is meshed by a gear 106 fast on a cross-shaft 107 journaled in bearings 80 108 in the main frame. The cross-shaft 107 is driven from the gear 32 fast on the shaft 30 of the transferrer, which meshes with a gear 110 journaled on a stud 111. The gear 110 meshes with a gear 114 on a stud 115 85 located in a bearing 116 of the main frame, the gear 114 meshing with one of the gears 106.

90 Each of the sprocket-wheels 98 is fast on a stud 117 journaled in a slide-bearing 118. Each of the slide-bearings is slidable lengthwise of a guide 119 and adjustable therein by means of a set-screw 120 locked in adjusted position by a jam-nut 121, the bearing being clamped in adjusted position 95 by a set-screw 122 received against said bearing through the wall of said guide. This adjustment is provided for properly stretching the sprocket-chains.

95 Preferably each of the sprocket-chains 100 has one of its links provided with a pin 123 on which there is a roll 124. Preferably each of the side-frames of the carriage has a guide 125, which extends crosswise of the stretches of the sprocket-chain, with which 105 the roll 124 cooperates. The stretches of the sprocket-chain have movement respectively in the directions of the arrows *a* and *b* (Fig. 4), and the carriage is moved in said respective directions by said pin, dependent on the stretch in which said pin is located at the time. The pin also moves about the outer portions of the sprocket-wheels at the respective ends of the sprocket-chain loop. When the pin passes about a 110 sprocket-wheel the speed of linear movement of the carriage is retarded, the retardation beginning when the pin arrives in the vertical plane of the axis of rotation of the sprocket-wheel, the carriage coming to a 115 stop when the pin arrives in the horizontal plane of the axis of rotation, the carriage then beginning its return travel with an accelerating movement while the pin is again moving toward the vertical plane of the 120 axis of rotation of the sprocket-wheel. This construction permits the reciprocating movement of the carriage to be brought to a gradual stop when the forward edge of the 125 sheet arrives at delivery position, for in- 130

stance adjacent to stops 126 adjustably positioned crosswise of the machine along a rod 127 secured to the main frame, thereby avoiding a nicking or damaging of the forward edge of the sheet so as to present a perfect edge to the feeding devices in subsequent printings of the sheet.

The construction further permits a return movement of the carriage to be initiated 10 with a gradually accelerating speed, so that the speed of contact between the rear edge of the sheet and the stripper devices may be regulated for effecting a stripping of the sheet off of the delivery-support without injury to the sheet.

If desired, the arrest of the sheet-delivery carriage may be further cushioned by buffers at the respective corners of said sheet-delivery carriage, shown accomplished by 20 means of pistons 128 secured to the respective corners of the sheet-delivery carriage, coöperating with cylinders 129 suitably secured to rigid parts of the frame of the machine, the cylinders being provided 25 with inlet-valves 130.

The stripper mechanism comprises stripper-fingers 136 having sheet-contact portions 137. The stripper-fingers are secured to blocks 138 positioned at suitable points 30 crosswise of the machine along a rock-shaft 139, being secured at suitable points lengthwise of said rock-shaft by set-screw 140. The rock-shaft is journaled in bearings 141 on blocks 142 having threaded engagement 35 with screw-rods 143 journaled in bearings 144, 145, of the main frame. The screw-rods are shown as operable in unison by being provided with bevel-pinions 146 with which bevel-pinions 147 fast on a cross-shaft 40 148 mesh, the cross-shaft being journaled in bearings 149 of the main frame and operable through suitable means, as a crank-handle 150.

In order to rock the stripper fingers 136 I 45 provide an arm 153 rigidly secured to the rock-shaft 139. This arm is movable with the rock-shaft in the adjustments of the latter lengthwise of the direction of movement of the sheet being delivered, and has 50 means coöperating therewith for rocking the same, these means maintaining their operative relations for rocking the rock-shaft throughout the adjustments of the latter. In the form shown the arm 153 has a pin 55 154 extending therefrom on which there is a roll 155. This roll coöperates with the walls of a slot 156 extending lengthwise of a bar 157. The bar is articulated at 158, 159, to arms 160, 161, articulated at 162, 60 163, to uprights 164, 165, rigid with the main frame. A pin 168 extends from the bar 157.

This pin is received in a slot 170 on a lever 171, pivoted on a stud 172 to the main frame, and having a roll 173 at its other

end which is contacted by a cam 174 secured 65 to and rotating with a gear 175. This gear rotates on a stud 176 extending from the main frame, and is meshed by a gear 177 fast on the shaft 30 of the sheet transferrer, for insuring proper timing of operation of 70 the strippers with relation to the time of delivery of the sheet by the transferrer.

When the high point of the cam strikes the roll 173, the bar 157 is raised for raising the pin 154 which is in the slot 156, irrespective of the position of the blocks 142 lengthwise of the machine, this pin being moved lengthwise in said slot by the mere adjustment of said blocks. The raising of the bar 157 raises the sheet-contact parts of 80 the stripper-fingers for permitting the sheet to pass the same in the sheet-delivery movement of the carriage 81.

The slot 156 extends substantially throughout the full range of adjustment of 85 said blocks, so that the rock-shaft 139 will be operated for operating the stripper-fingers irrespective of the position of said blocks 142. The bar 157 is maintained parallel by the connection of the arms 160, 161, 90 therewith.

When the high point of the cam passes the roll 173, the bar 157 will be lowered, which may be influenced by means of a spring 178, the ends of which are secured 95 respectively to the lever 171 and a suitable point on the frame. The sheet-contact portions 137 of the stripper-fingers are thereby brought into range with the sheet and preferably extend at right angles to the plane of 100 said sheet.

The parts are preferably so adjusted that, when the sheet is located at its limit of delivery movement, the said sheet-contact portions of said stripper-fingers are preferably slightly distanced from the rear edge of said sheet, so that, upon the return movement of the delivery-sticks, the rear edge of the sheet will contact said stripper-fingers with a slight blow, the force of which is 110 engaged by the distance of said contact-portions of said stripper-fingers from said rear edge of said sheet and the accelerating movement imparted to the sheet by the sprocket-chain and pin and guide connection with the carriage. The sheet preferably lies upon the delivery-sticks in sagging form between the delivery-sticks for giving additional rigidity to the sheet across its width. Upon retraction of the delivery-sticks, the sheet drops 115 120 into a suitable receptacle 179, provided with suitable jogging mechanism, not shown because well known.

The stripper-fingers are shown of angular form and are also adjustable about the axis 125 of the rock-shaft to permit any one or more of the fingers to be swung around the shaft into inoperative position and for insuring

that the sheet-contacting portions 137 of the stripper-fingers shall have the proper angularity with relation to the plane of the sheet.

Having thus fully described my invention, what I claim as new and desire to secure by Letters Patent, is:

1. In sheet delivery mechanism of the character described, the combination of a sheet-transferrer, a reciprocating sheet-receiving device, and a stripper mechanism for the latter comprising stripper-fingers, a support for said stripper-fingers and means for adjusting said support toward and from said sheet-transferrer comprising an articulated connection the parts whereof have relative adjustment between them during said first-named adjustment and are maintained in operative relation for operating said stripper-fingers during said adjustment.
2. In sheet delivery mechanism of the character described, the combination of a sheet-transferrer, a reciprocating sheet-receiving device, stripper mechanism comprising stripper-fingers, and means for operating said reciprocating sheet-receiving device and stripper mechanism having driven connection with said sheet-transferrer, said means comprising an articulated connection and adjusting means for adjusting the operative relations in said articulated connection while maintaining the operative connections in said stripper-mechanism for operating said stripper-fingers.
3. In sheet delivery mechanism of the character described, the combination of a sheet-receiving device, a stripper mechanism therefor comprising a stripper-part, adjusting means for adjusting said stripper-part lengthwise of the path of the sheet and maintaining said stripper-part in adjusted positions during adjustment, and means for operating said stripper-part comprising a shiftable part shifted by said adjusting means and a coöperating part therefor maintained in operative relation with said shiftable part while adjusting said shiftable part.
4. In sheet delivery mechanism of the character described, the combination of a sheet-receiving device, a stripper mechanism therefor comprising a stripper-part, means for adjusting said stripper-part lengthwise of the path of the sheet with relation to said sheet-receiving device, and means for operating said stripper-part comprising an adjustable articulated connection having operative connection with said last-named adjusting means for moving said stripper-part while adjusting said stripper-part.
5. In sheet delivery mechanism of the character described, the combination of a sheet-receiving device, a stripper mechanism therefor comprising a stripper-part, means for adjusting said stripper-part lengthwise of the sheet-contact portions of said stripper-fingers from said rear edges of said
- of the path of the sheet, and means for operating said stripper-part comprising a bar, means for moving said bar laterally and means for maintaining said bar in parallel positions throughout its movements, said bar having operative articulated connection with said stripper-part for moving the same while adjusting said stripper-part.
6. In sheet delivery mechanism of the character described, the combination of a sheet-receiving device, a stripper-part therefor, a movable member for said stripper-part, means for adjusting said movable member lengthwise of the direction of travel of the sheet, an operating bar, means for transversely operating said operating bar, means for maintaining said operating bar parallel in various positions, and an operative articulated connection between said operating bar and said movable member the parts whereof have adjustment therebetween by said first-named adjusting means while being maintained in continuous operative condition while adjusting said movable member.
7. In sheet delivery mechanism of the character described, the combination of a sheet-receiving device, a stripper-part therefor, a rocking member on which said stripper-part is mounted, means for adjusting said rocking member lengthwise of the path of travel of the sheets, an arm for rocking said rocking member, an operating bar with which said arm has articulated operative connection at the various positions of adjustment of said rocking member and while adjusting said rocking member for operating said rocking member, and means for transverse reciprocation of said operating bar for rocking said rocking member in the various adjusted positions of the latter and while adjusting the same.
8. In sheet delivery mechanism of the character described, the combination of a reciprocating sheet-receiving device, an endless flexible propelling means arranged in a pair of oppositely moving stretches and a pair of rounded directing parts about which said flexible propelling means is received loopwise at the ends of said stretches, coacting means between said flexible propelling means and reciprocating sheet-receiving device for imparting alternate retarding and accelerating movements to said sheet-receiving device at the limits of reciprocating movements of the latter, stripper-fingers coacting with said sheet-receiving device for stripping the sheets therefrom, and means for adjusting said stripper-fingers lengthwise of the path of travel of the sheet for adjusting said stripper-fingers toward and from the rear edges of the sheets for determining the distance of the sheet-contact portions of said stripper-fingers from said rear edges of said

sheets and the speed of said sheets upon contact thereof with said sheet-contact portions of said stripper-fingers.

9. In sheet delivery mechanism of the character described, the combination with a sheet-receiving device, of a stripper mechanism therefor comprising stripper-fingers, a rock-shaft for said fingers, adjustable blocks in which said rock-shaft is journaled, screw-rods having threaded engagement with said blocks, turning means for said screw-rods for adjusting said blocks lengthwise of the path of travel of the sheet, and means having operative connection with said rock-shaft throughout its positions of adjustment for rocking the same.

10. In sheet delivery mechanism of the character described, the combination with a sheet-receiving device, of a stripper mechanism therefor comprising stripper-fingers, a rock-shaft for said fingers, adjustable blocks in which said rock-shaft is journaled, screw-rods having threaded engagement with said blocks, turning means for said screw-rods for adjusting said blocks lengthwise of the path of travel of the sheet, and means having operative connection with said rock-shaft throughout its positions of adjustment for rocking the same, comprising an arm secured to said rock-shaft, a bar extending lengthwise of said path, means for maintaining said bar parallel in its various positions, operative connection between said arm and bar maintained throughout the positions of adjustment of said rock-shaft, and a lever for moving said bar transversely and thereby rocking said arm and rock-shaft.

11. In sheet delivery mechanism of the

character described, the combination with a sheet-receiving device, of a stripper mechanism therefor comprising stripper-fingers, a rock-shaft for said stripper-fingers, adjustable blocks in which said rock-shaft is journaled, screw-rods having threaded engagement with said blocks, turning means for said screw-rods for adjusting said blocks lengthwise of the path of travel of the sheet, and means having operative connection with said rock-shaft throughout its positions of adjustment for rocking the same comprising an arm secured to said rock-shaft, a bar extending lengthwise of said path, means for maintaining said bar parallel in its various positions, and means for moving said bar into said various positions having operative connection with said transverser.

12. In sheet delivery mechanism of the character described, the combination of a sheet-transferrer, a sheet-receiving device, a stripper mechanism for the latter comprising stripper-fingers, a rocking member therefor, means for adjusting said rocking member toward and from said sheet-transferrer, and means for operating said rocking member having operative connection with said transferrer and operative connection with said rocking member for rocking the same in its various positions of adjustment and while said rocking member is being adjusted.

In testimony whereof, I have hereunto signed my name in the presence of two subscribing witnesses.

FREDERICK H. BEROLD.
